UNITED STATES PATENT OFFICE

125,192

DESIGN FOR A WINDSHIELD SERVICE CABINET

Lawrence V. Shepherd, Van Nuys, Calif.

Application June 24, 1940, Serial No. 93,218

Term of patent 7 years

To all whom it may concern:

Be it known that I, Lawrence V. Shepherd, citizen of the United States and residing at 6958 Woodman Avenue, Van Nuys, California, have invented a new, original, and ornamental Design for a Windshield Service Cabinet, of which the following is a specification, reference being had to the accompanying drawing, forming part thereof.

Figure 1 is a front perspective view of a windshield service cabinet, showing my new design.

Figure 2 is a rear perspective view of said windshield service cabinet.

I claim:

The ornamental design for a windshield service cabinet, substantially as shown.

LAWRENCE V. SHEPHERD.
